LIFTING DEVICE

John S. Pehrsson, Elyria, Ohio, assignor of one-half to John M. Gemberling, Lakewood, Ohio

Application August 14, 1930. Serial No. 475,183

6 Claims. (Cl. 254—131)

My invention relates to a lifting device. It has to do more particularly with that type of device which will lift heavy objects to such a position that a dolly or rollers may be placed thereunder.

In the past, to lift heavy objects to a height great enough to insert rollers it has been necessary to use a block and a crow bar to first lift one end and then repeat the operation on the other side. It has often been advisable to block up the object by first placing a small block under one end then under the other end, and by steps repeating the operation to increase the height of blocks until the desired position has been obtained. In other cases the procedure has been to have a group of men first tip the object on one end then place a roller or dolly thereunder and then lift the object onto the carrying means. In the case of heavy objects of furniture or cases such as refrigerators and the like the use of a bar has a tendency to mar the beauty of the object and hence reduce the value thereof or causes loss to the movers. Furthermore the present methods of lifting heavy objects of this type requires the services of too many men to handle the job economically.

One of the objects of my invention is to provide a means for lifting heavy objects to a position where a dolly or the like may be placed thereunder.

Another object of my invention is to provide an elevating device which will lift one end of an object to a predetermined position and to assure the maintenance of the position until the opposing end can be lifted.

Another object of my invention is to provide a means of lifting furniture such as refrigerators and the like without damage thereto and with as few men as possible.

My invention comprises generally two frame castings disposed in spaced relation on a tilting rod. This framework is adapted to have pivotally mounted thereon a supporting surface. The rocking of the cradle so formed is effective to raise or lower the supporting surface.

Further objects and advantageous features will be apparent from the following detailed description wherein similar characters of reference designate corresponding parts and wherein:

Fig. 1 is a perspective view partly broken away showing the preferred form of my invention in assembled relation and holding an object in elevated position;

Fig. 2 is a front elevation partly broken away, 55 of my lifting device;

Fig. 3 is a side elevation of the device shown in Fig. 2 and

Fig. 4 is a plan view of my lifting device showing the tilting bar assembled thereto.

With reference to the drawing, I have shown the preferred embodiment of my invention wherein the lifting device is composed of two castings or cam elements 10 of similar construction and which are disposed in spaced relation on the tubular tilting bar 11. The castings 10 have a cylindrical boss 12 extending from opposing sides of the castings and which are centrally bored to receive the tilting bar 11. Pins 13 extend through the bosses and through the bar 11 to secure the bar in fixed relation upon the castings.

The castings 11 have a bearing surface 14 formed upon one side thereof which is adapted to engage the floor and support the load when the object is in raised position. Adjacent the bearing surface 14 are the bearings 15 which are adapted to receive the opposing ends of the roller shaft 16 upon which is rotatably mounted the roller 17. In raising an object the device is rotated about the roller 17 and onto the bearing surface 14. These bearing surfaces 14, when in contact with the floor permit the shaft 20 upon which the platform is mounted to lie in a plane beyond the vertical center of the roller shaft 16, thereby shifting the center of gravity to a point which will assure the retention of the device in this position.

A lug 18 formed integrally with the body portion of the casting and extended therefrom forms a bearing surface 19 when the device is in lowered position. Apertures 19a disposed in the lugs 18 receive a shaft 20. A platform of angular cross section has depending flanges 22 formed on the opposing sides of the bottom plate 23. The flanges 22 are provided with apertures 24 through which the shaft 20 passes. The platform 21 is mounted freely on the shaft so that it may find the suitable angulated relation to the object to be elevated when adjusted thereto. A pad 25 of rubber or other suitable material is secured to the faces of the platform to circumvent the slipping or defacement of the object being lifted.

The tilting bar 11 may be made as shown of tubular stock the outer extended end thereof being formed to accommodate a wrench or bar to facilitate rolling or turning the device about its fulcrum roller 17.

In operation the apparatus is set in the position as shown in Fig. 3. Assuming the object to be moved has been tipped or raised to permit the

bottom plates 23 of each of the devices to be slid thereunder. A wrench or bar is then applied to the end of the tilting rod 11 and the frame is revolved about the fulcrum roller as indicated by 5 the arrow in Fig. 3. The device will then take the position as shown in Fig. 1 with the object in raised position to place a dolly or rollers thereunder.

It will be apparent from the foregoing description that I have provided a lifting device of such 10 structure that heavy objects having their bottom resting on the floor or relatively close thereto may be easily elevated by one man to such a position that a dolly or similar means for moving 15 such object may be inserted thereunder.

While the foregoing description is necessarily 20 of a detailed character it is to be understood that the specific terminology employed is not to be construed as restrictive or limiting, and it is to be further understood that various rearrangements of parts and modifications may be resorted to without departing from the scope or spirit of the invention as claimed herein.

I claim:

- 25 1. A lifting device comprising spaced cam-acting frame members having in general a triangular contour with one side of the triangle serving as a load supporting bearing surface, a tilting bar projecting through and rigidly secured to said frame members and provided with a handle extremity projecting from one side thereof, and an angle-shaped platform pivotally mounted at one extremity of said members, the handle extremity of said bar serving as a lever which when rotated 30 initiates a cam action to said frame members and turns them together with the load about one extremity of the triangle and throws the load past the center of gravity of the frame members onto the bearing surface thereof.
- 35 2. A lifting device comprising spaced cam-acting frame members having in general a triangular contour, one of the sides of the triangle being formed substantially flat to serve as a load-supporting bearing surface, a tilting bar rigidly secured to said frame members and provided with a handle extremity projecting at right angles therefrom, and an angle-shaped load-engaging platform pivotally mounted at the extremity of the triangle which lies substantially opposite the said bearing side, the handle extremity of said bar serving as a lever which when rotated initiates a cam action to said frame members and turns them together with the load about one extremity of the triangle and throws the load past the center of gravity of said members onto said bearing surface.
- 40 3. A lifting device comprising spaced cam-acting frame members having in general a triangular contour, one of the sides of the triangle being formed substantially flat to serve as a load-supporting bearing surface, a tilting bar rigidly secured to said frame members and provided with a handle extremity projecting at right angles therefrom, an angle-shaped load-engaging platform pivotally mounted 45 at the extremity of the triangle which lies substantially opposite the said bearing side, the handle extremity of said bar serving as a lever which when rotated initiates a cam action to said frame members and turns them together with the load about one extremity of the triangle and throws the load past the center of gravity of said members onto said bearing surface.
- 50 4. A lifting device comprising spaced cam-acting frame members having in general a triangular contour, one of the sides of the triangle being formed substantially flat to serve as a load-supporting bearing surface, a tilting bar rigidly secured to said frame members and provided with a handle extremity projecting at right angles therefrom, an angle-shaped load-engaging platform pivotally mounted 55 at the extremity of the triangle which lies substantially opposite the said bearing side, the handle extremity of said bar serving as a lever which when rotated initiates a cam action to said frame members and turns them together with the load about one extremity of the triangle and throws the load past the center of gravity of said members onto said bearing surface.
- 60 5. A lifting device comprising spaced cam-acting frame members having in general a triangular contour, one of the sides of the triangle being formed substantially flat to serve as a load-supporting bearing surface, a tilting bar projecting through and rigidly secured to said frame members and provided with a handle extremity projecting at right angles therefrom, an angle-shaped load-engaging platform pivotally mounted 65 at the extremity of the triangle which lies substantially opposite the said bearing side, the handle extremity of said bar serving as a lever which when rotated initiates a cam action to said frame members and turns them together with the load about one extremity of the triangle and throws the load past the center of gravity of said members onto said bearing surface.

at the extremity of the triangle which lies substantially opposite the said bearing side, the handle extremity of said bar serving as a lever which when rotated initiates a cam action to said frame members and turns them together with the load about one extremity of the triangle and throws the load beyond the center of gravity of said members onto said bearing surface, and a bearing roller for supporting the load while turning the frame members.

4. A lifting device comprising spaced cam-acting frame members having in general a triangular contour, a tilting bar rigidly secured to said frame members and provided with a handle extremity projecting at right angles therefrom, an open-sided angle-shaped load-engaging platform pivotally mounted at one extremity of the triangle, the handle extremity of said bar serving as a torque lever which when rotated initiates a cam action to said frame members and turns them together with the load-engaging platform past the center of gravity of said members onto the opposite side of the triangle.

5. A lifting device comprising spaced cam-acting frame members at least two sides of which have substantially a right angular contour, one of the sides of the angle being formed substantially flat to serve as a load-supporting bearing surface, a tilting bar projecting through and rigidly secured to said frame members and provided with a handle extremity projecting at right angles therefrom, an open-sided angle-shaped load-engaging platform pivotally mounted at the one extremity of the angles which lies substantially opposite the said bearing side, the handle extremity of said bar serving as a lever which when rotated initiates a cam action to said frame members and turns them together with the load about the apex of the angle and throws the load past the center of gravity of said members onto said bearing surface, and a bearing located at the apex of the angle for supporting the load during the turning movement.

6. A lifting device comprising spaced cam-acting frame members each having two sides thereof formed at substantially right angles with respect to one another, one side of the angle serving as a bearing surface while the load is being engaged and the opposite side of the angle serving as a bearing surface for supporting the load after the lifting operation, a tilting bar projecting through and rigidly secured to said frame members and provided with a handle extremity projecting at right angles therefrom, an angle-shaped open-sided load engaging platform pivotally mounted at the extremity of the angle, the handle extremity of said bar serving as a lever which when rotated initiates a cam action to said frame members and turns them together with the load about one extremity of the angle and throws the load past the center of gravity of said members onto said second named bearing surface, and a bearing roller mounted in the extremity of the angle which supports the load during the turning operation.

JOHN S. PEHRSSON. 140
